Primary Examiner — Ricky Pham(74) *Attorney, Agent, or Firm* — Banner & Witcoff, Ltd.(57) **CLAIM**

The ornamental design for a cookware assembly, as shown and described.

DESCRIPTION

FIG. 1 is a perspective view of a cookware assembly showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The dotted lines represent portions of the cookware assembly that form no part of the claimed design. The dot-dash-dot lines represent boundaries between claimed and unclaimed subject matter.

1 Claim, 5 Drawing Sheets(56)
